(57) **CLAIM**

The ornamental design for a fan blade, as shown and described.

DESCRIPTION

FIG. 1 is a front elevational view of a fan blade showing my new design;

FIG. 2 is a rear elevational view showing the design for the fan blade of FIG. 1;

FIG. 3 is a right side elevational view showing the design for the fan blade of FIG. 1;

FIG. 4 is a left side elevational view showing the design for the fan blade of FIG. 1;

FIG. 5 is a top plan view showing the design for the fan blade of FIG. 1;

FIG. 6 is a bottom plan view showing the design for the fan blade of FIG. 1; and,

FIG. 7 is a perspective view showing the design for the fan blade of FIG. 1.

In FIGS. 1–7, broken line showing of various items including (i) a proximal area of the fan blade including the mounting region of the fan blade, (ii) the substantially circular feature spaced inwardly of the substantially circular support ring (FIG. 2), and (iii) the generally linear creases located at the peripheral edge of the fan blade (FIGS. 3–7) is for illustrative purposes only and forms no part of the claimed design.
